UNITED STATES PATENT OFFICE.

ANTON BAUMEISTER, OF GROTON, SOUTH DAKOTA.

ELLIPSOGRAPH.

1,224,591.

Specification of Letters Patent.

Patented May 1, 1917.

Application filed August 12, 1916. Serial No. 114,609.

To all whom it may concern:

Be it known that I, ANTON BAUMEISTER, a subject of the Emperor of Germany, residing at Groton, in the county of Brown and 5 State of South Dakota, have invented certain new and useful Improvements in Ellipsographs; and I do hereby declare the following to be a full, clear, and exact description of the invention, such as will enable 10 others skilled in the art to which it appertains to make and use the same.

This invention relates to improvements in drafting instruments, and has for its primary object to provide an improved ellipsograph embodying novel features of construction whereby the instrument may be quickly and conveniently adjusted to describe ellipses of various shapes and sizes.

With this and other objects in view the 20 invention consists in the novel construction, combination and arrangement of parts as will be hereinafter more fully described, claimed and illustrated in the accompanying drawings, in which:

25 Figure 1 represents a perspective view of the ellipsograph,

Fig. 2 represents a side elevation thereof, and

Fig. 3 represents a longitudinal sectional view on the line 3—3 of Fig. 1.

Referring to the drawing in detail, wherein similar reference numerals designate corresponding parts throughout the several views, the numeral 5 indicates the main or 35 center leg of the ellipsograph which is formed at its lower terminal with the usual centering point 6. Adjacent its upper terminal the leg 5 is pivotally connected at 7 with a pair of adjustable bracing legs 8, 40 having pointed lower terminals 9 for anchoring the bracing legs in position.

Adjacent the upper terminal of the leg 5 the latter is offset, as indicated at 10, and is provided with a pair of forwardly directed 45 spaced parallel arms 11, which are pivotally connected at 12 with the parallel ends 13 of a U-shaped member, designated generally by the numeral 14. The web portion 15 of the U-shaped member 13 is formed with an 50 integral hollow collar 16 in which is rotatably mounted the upper section 17 of a shaft, the lower section 18 of which is connected with the upper section by a pivot pin 19, whereby the angular position of the 55 two sections may be varied as desired.

The several sections 20 forming the leg,

designated generally by the numeral 21, are pivotally connected by joints 22 and the section at one end of the leg is formed with an 60 enlargement 23, which is rigidly secured to the upper shaft section 17 and is confined between the head 24 of said shaft section and the collar 16 of the U-shaped member 14. The section at the opposite end of the leg 21 is provided with a preferred type of 65 marker 25, which may be adjusted with relation to the point 6 of the center leg 5 by swinging the sections 20 upon their pivotal axes 22.

An L shaped bearing member 26 is pivotally secured to the upper terminal of the center leg 5 between the arms 11 by a pin 27, which is disposed at right angles to the pivotal connection between the legs of the U-shaped member 14 and the arms 11. The 75 horizontally disposed end of the member 26 is formed with a substantially semispherical recess or socket 28 in which is fitted the rounded lower terminal 29 of the lower shaft section 18.

The lower shaft section 18 is secured in 80 adjusted angular position with relation to the upper shaft section 17 by the friction produced at the pivotal connection or joint 19 between these parts, and the L-shaped 85 member 26 is likewise secured in adjusted position with relation to the upper terminal of the center leg 5 by the friction between said bearing member and the upper terminal of the leg at the pivotal connection 27. 90

In use, the shape of the figure described by the marker E, as the latter rotates with the shaft sections 17 and 18, may be varied, as desired, by adjusting the lower shaft section 18 at the proper angle with relation to 95 the upper shaft section 17, while the size of the figure described by the marker may be varied as desired by moving the marker inwardly toward or away from the point 6 of the center leg 5. As the shaft sections 17 100 and 18 are rotated with the marker E in the act of describing a figure, the angular lower section 18 causes the U-shaped member 14 to oscillate, thus moving the marker E toward and away from the center leg 5 and 105 causing said marker to describe an ellipse or arc.

What I claim is:

1. An ellipsograph comprising a center leg having a pointed end, a pair of spaced 110 parallel arms connected with said leg, a U-shaped frame connected with said arms,

a shaft including angularly adjustable sections, one of said sections being journaled in the web portion of said U-shaped member, a leg connected with the upper shaft section, a marker connected with said leg, and means connected to said leg to rotatably receive the lower terminal of the lower shaft section.

2. An ellipsograph including a center leg, 10 a pair of spaced parallel arms carried by said leg, a U-shaped member connected at its ends with said arms, a shaft including pivoted and relatively adjustable sections, the upper shaft section being journaled in 15 the U-shaped member, a bearing member pivotally secured to the center leg engaging the lower terminal of the lower shaft section, and a marker rigidly connected with the upper shaft section including a plurality 20 of relatively adjustable sections.

3. An ellipsograph including a center leg, a pair of spaced parallel arms connected with the upper terminal of said leg, an inverted U-shaped member having the free 25 ends pivotally connected with said arms, a shaft including pivotally connected and relatively adjustable sections, one of said sections being rotatably mounted in the web portion of the U-shaped member, an L-shaped member pivotally secured to said center leg and having its axis arranged at right angles to the pivotal axis of the U-shaped member, a socket carried by said L-shaped member pivotally receiving the 30

lower terminal of the lower shaft section, 35 a leg non-rotatably secured to the upper shaft section, and a marker carried by said leg.

4. An ellipsograph including a center leg, a pair of auxiliary bracing legs pivotally secured to said center leg, a rotatable marker, and means connecting said marker with said center leg whereby the distance between the latter and said marker is varied during rotary movement of the marker. 40

5. An ellipsograph including a center leg, members pivotally secured to said leg and having their axes angularly disposed, a shaft including a pair of pivotally connected sections supported by said pivoted members, 50 and a marker connected with one of the shaft sections.

6. An ellipsograph including a leg, a member pivotally secured to said leg, a second member pivotally secured to said leg 55 and having its axis arranged at right angles to the axis of the first-mentioned member, a shaft including a pair of pivoted and angularly adjustable sections supported in said pivoted members, and a marker connected 60 with one of the shaft sections.

In testimony whereof I affix my signature in presence of two witnesses.

ANTON BAUMEISTER.

Witnesses:

EDWARD NEUMAN,
E. E. KVITRUD.
